The ornamental design for a control grip, as shown and described.

DESCRIPTION

FIG. 1 is an oblique view of a right-hand control grip (a left-hand control grip is a mirror image and is not shown). FIG. 2 is a front elevational view of the control grip of FIG. 1.

FIG. 3 is a rear elevational view of the control grip of FIG. 1.

FIG. 4 is a right side elevational view of the control grip of FIG. 1.

FIG. 5 is a left side elevational view of the control grip of FIG. 1.

FIG. 6 is a top plan view of the control grip of FIG. 1; and, FIG. 7 is a bottom plan view of the control grip of FIG. 1. The second embodiment of the control grip is a mirror image of the embodiment disclosed in FIGS. 1 through 7 and is not shown. Broken-line illustration of environmental structure in the drawing, namely, a thumbwheel, a grip base, and a system housing, is not part of the design sought to be patented.
